UNITED STATES PATENT OFFICE.

RICHARD J. RILEY, OF JENNINGS, MISSOURI.

CLOTHESLINE PROP.

Application filed July 2, 1923. Serial No. 649,062.

To all whom it may concern:

Be it known that I, RICHARD J. RILEY, a citizen of the United States, residing at Jennings, in the county of St. Louis and State 5 of Missouri, have invented certain new and useful Improvements in Clothesline Props, of which the following is a specification, reference being had therein to the accompanying drawing.

10 The present invention relates to clothes line props, and aims to provide novel and improved means for fastening the prop and line together to prevent accidental separation thereof, as well as preventing the line 15 and prop from moving out of position relatively to one another.

Another object is the provision of a line gripping member of novel formation to be carried by a clothes line prop, which member 20 can be readily bent from wire, and which will effectively and conveniently fasten the line to the prop.

With the foregoing and other objects in view, which will be apparent as the description 25 proceeds, the invention resides in the construction and arrangement of parts as hereinafter described and claimed, it being understood that changes can be made within the scope of what is claimed, without departing from the spirit of the invention.

30 The invention is illustrated in the accompanying drawing, wherein—

Figure 1 is a side elevation of the upper terminal of a clothes prop showing the 35 gripping member or clip thereon in open or released position.

Fig. 2 is a similar elevation showing the gripping member or clip in closed or gripping position.

40 Fig. 3 is an edge view with the clip in the position as shown in Fig. 2.

Figs. 4 and 5 are cross sections on the respective lines 4—4 and 5—5 of Fig. 2.

The clothes line prop 7, usually 45 constructed of wood, is provided near its upper end with an inclined slot 8 opening at one edge of the prop for receiving the clothes line 9, said slot being provided at its inner end with a downwardly extending notch 50 or seat 10 for the line.

The line gripping member or clip 11 is disposed at one side of the prop, and is slideable in the transverse wire guides 12, 13 and 14 disposed at said side of the prop and having 55 their terminals engaged or driven into the prop, as seen in Fig. 4. Said guides

guide the clip 11 for longitudinal sliding movement and also holds the clip against the side of the prop.

The clip or member 11 is bent from a 60 length of resilient wire, and has the upwardly-extending arms 15 slideable behind the guides 12, 13 and 14, with the terminals of the wire at the upper ends of said arm bent into eyes 16 providing finger pieces 65 for springing of the arms 15 toward one another and to slide the clip lengthwise. The clip 11 has V-shape gripping or pinching portion 17 disposed between and connecting the lower ends of the arms 15 and 70 8. The arms 15 are provided between their ends with offsets or shoulders 18 to move below the guide 13 and to engage under the end portions of said guide when the clip is 75 slid downwardly to gripping position, as seen in Fig. 2.

In order to limit the upward movement of the clip and to prevent the withdrawal of the clip from the prop, pins or stops 19 80 are driven or engaged in the side of the prop under the guide 13 and above the slot 8, between the arms 15, for the contact of said arms when the switch is slid upwardly to raise the arms 15 and portion 17 above 85 the slot, as seen in Fig. 1. The stops 19 have their outer ends bent at an angle, as at 20, to engage across the arms 15 when the clip is in raised position.

When the clip 11 is in raised position, as 90 seen in Fig. 1, it is retracted from the slot 8, thereby permitting the clothes line 9 to be moved into or removed from the slot 8. In order to grip the line and secure it to the prop, the clip 11 is slid downwardly, thereby 95 projecting same across the slot 8 and behind the guide 14, and the V-shaped gripping portion 17 will grip the line 9, said line being wedged into the portion 17, so as to be pinched by said portion, the portion 17 100 springing open slightly, due to its resiliency, in order to grip or pinch the line between the arms or side portions thereof. In the gripping position of the clip 11, the offsets or shoulders 18 are moved below the guide 13, 105 and the arms 15 springing apart will move said offsets or shoulders under the end portions of the guide 13, thereby preventing the clip from moving upwardly accidentally relatively to the prop. This will retain the 110 clip in gripping position. By pressing the finger pieces 16 toward one another to spring

the arms 15 toward one another, the offsets or shoulders 18 are moved toward one another sufficiently so that they can pass upwardly through the guide 13. The clip can then be slid upwardly to retract it from the slot 8 and line 9, whereby the prop and line can be separated. The stops 19 limit the upward movement of the clip.

10 The clip 11, guides 12, 13 and 14 and stops 19 are all composed of wire, so as to be inexpensively made.

Having thus described the invention, what is claimed as new is:—

15 1. A clothes line prop having a line receiving slot, a line gripping clip having resilient arms and a V-shaped gripping portion between said arms to move across said slot for gripping the line in said portion, and guiding means for the clip carried by 20 the prop, said arms being engageable with said guiding means to hold the clip in line gripping position and having finger pieces for disengaging the arms from said means and for moving the clip in said means from 25 said position.

2. A clothes line prop having a line receiving slot, a line gripping resilient clip having arms and a V-shaped gripping portion between said arms to move across said slot for gripping a line in said portion, and guiding means for the clip in which said arms are movable toward and away from said slot, said arms having finger pieces for moving said clip.

3. A clothes line prop having a line receiving slot, a line gripping clip to project across said slot for gripping the line, and guiding means for the clip carried by the prop in which the clip is slidable, said clip having resilient means to engage the guiding means when the clip is in line gripping position to hold the clip in such position and adapted to

be sprung out of engagement from said means for sliding the clip from said position.

4. A clothes line prop having a line receiving slot, a line gripping clip having a gripping portion to project across said slot for gripping the line, and guiding means for the clip carried by said prop in which the clip is slidable, the clip having resilient portions to engage the guiding means for holding the clip in line gripping position and adapted to be sprung out of engagement from said means for sliding the clip from such position.

5. A clothes line prop having a line receiving slot, a line gripping clip having a line gripping portion to extend across said slot and grip the line, and guiding means for the clip carried by the prop in which the clip is slidable, said clip having resilient arms with offsets to engage said guiding means when the clip is slid to gripping position to hold the clip in such position and adapted to be disengaged from the guiding means by 65 springing said arms toward one another to permit the clip to be slid from such position.

6. A clothes line prop having a line receiving slot, a line gripping clip having resilient arms and a V-shaped gripping portion between said arms to move across said slot for gripping the line in said portion, and guiding means for the clip carried by the prop, said arms having offsets to engage the guiding means when the clip is in gripping position to hold the clip in said position, and said arms having finger pieces for springing the arms toward one another to disengage said offsets from the guiding means.

In testimony whereof I hereunto affix my signature.

RICHARD J. RILEY.
